(57) **CLAIM**

The ornamental design for a pet toy set, as shown and described.

DESCRIPTION

FIG. 1 is an exploded perspective view of a pet toy set in an open configuration, showing my new design;

FIG. 2 is a front, top perspective view of a first piece of the pet toy set;

FIG. 3 is a rear, top perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is a front, top perspective view of a second piece of the pet toy set;

FIG. 11 is a rear, top perspective view thereof;

FIG. 12 is a front view thereof;

FIG. 13 is a rear view thereof;

FIG. 14 is a left side view thereof;

FIG. 15 is a right side view thereof;

FIG. 16 is a top view thereof;

FIG. 17 is a bottom view thereof;

FIG. 18 is a front, top perspective view of a third piece of the pet toy set;

FIG. 19 is a rear, top perspective view thereof;

FIG. 20 is a front view thereof;

FIG. 21 is a rear view thereof;

FIG. 22 is a left side view thereof;

FIG. 23 is a right side view thereof;

FIG. 24 is a top view thereof;

FIG. 25 is a bottom view thereof;

FIG. 26 is a front, top perspective view of a fourth piece of the pet toy set;

FIG. 27 is a rear, top perspective view thereof;

FIG. 28 is a front view thereof;

FIG. 29 is a rear view thereof;

FIG. 30 is a left side view thereof;

FIG. 31 is a right side view thereof;

FIG. 32 is a top view thereof;

FIG. 33 is a bottom view thereof;

FIG. 34 is a front, top perspective view of a fifth piece of the pet toy set;

FIG. 35 is a rear, top perspective view thereof;

FIG. 36 is a front view thereof;

FIG. 37 is a rear view thereof;

FIG. 38 is a left side view thereof;

FIG. 39 is a right side view thereof;

(Continued)

FIG. 40 is a top view thereof;
 FIG. 41 is a bottom view thereof;
 FIG. 42 is a front, top perspective view of a sixth piece of the pet toy set;
 FIG. 43 is a rear, top perspective view thereof;
 FIG. 44 is a front view thereof;
 FIG. 45 is a rear view thereof;
 FIG. 46 is a left side view thereof;
 FIG. 47 is a right side view thereof;
 FIG. 48 is a top view thereof;
 FIG. 49 is a bottom view thereof;
 FIG. 50 is a front, top perspective view of a seventh piece of the pet toy set;
 FIG. 51 is a rear, top perspective view thereof;
 FIG. 52 is a front view thereof;
 FIG. 53 is a rear view thereof;
 FIG. 54 is a left side view thereof;
 FIG. 55 is a right side view thereof;
 FIG. 56 is a top view thereof;
 FIG. 57 is a bottom view thereof;
 FIG. 58 is a front, top perspective view of an eighth piece of the pet toy set;
 FIG. 59 is a rear, top perspective view thereof;
 FIG. 60 is a front view thereof;
 FIG. 61 is a rear view thereof;
 FIG. 62 is a left side view thereof;
 FIG. 63 is a right side view thereof;
 FIG. 64 is a top view thereof;
 FIG. 65 is a bottom view thereof;
 FIG. 66 is a front, top perspective view of a ninth piece of the pet toy set;
 FIG. 67 is a rear, top perspective view thereof;
 FIG. 68 is a front view thereof;
 FIG. 69 is a rear view thereof;
 FIG. 70 is a left side view thereof;
 FIG. 71 is a right side view thereof;
 FIG. 72 is a top view thereof; and,
 FIG. 73 is a bottom view thereof.

The broken lines in the figures illustrate portions of the pet toy set that form no part of the claimed design.
